UNITED STATES PATENT OFFICE.

ADAM J. HOBART, OF ST. JOHNSVILLE, NEW YORK, ASSIGNOR TO ROTH AND ENGELHARDT, OF NEW YORK, N. Y., A FIRM.

COIN-CONTROLLED ACTUATING MECHANISM FOR AUTOPNEUMATIC PIANOS.

SPECIFICATION forming part of Letters Patent No. 786,899, dated April 11, 1905.

Application filed July 11, 1904. Serial No. 215,989.

To all whom it may concern:

Be it known that I, ADAM J. HOBART, a citizen of the United States, residing at St. Johnsville, Montgomery county, State of New York, have invented new and useful Improvements 5 in Coin-Controlled Actuating Mechanism for Autopneumatic Pianos, of which the following is a specification.

This invention relates to improved means 10 for starting an autopneumatic piano or piano-player by the introduction of a coin and for arresting the same after the piece has been played.

In the accompanying drawings, Figure 1 is 15 a front elevation of my improved coin-controlled actuating mechanism; Fig. 2, a detail front elevation of the switch, showing it open; Fig. 3, a plan; Fig. 4, a side view thereof, and Fig. 5 a detail cross-section through the vacuum-chest and tracker-bar.

The letter *a* represents the power-shaft of 20 an autopneumatic piano or piano-player, which receives its motion from the driving-shaft *b* of an electromotor *b* by pulleys *b*² *a*² and rope *a*². *c* is the tracker-bar or duct-bridge, and *d* the feed-roller for the perforated music-sheet, all as usual.

In order to start the electromotor by the introduction of a coin and arrest the same after 25 a piece of music has been played, I have devised the following construction: *e* is the coin-chute, and *f* a two-arm lever, which is fulcrumed to a frame *g* at *f*' and is provided with a coin-rest *f*² below chute *e*. When a 30 coin is dropped into the chute, it will fall upon rest *f*² to tilt lever *f* and will then drop into a cash-box *h*, after which the lever *f* will be returned to its normal position by a spring *f*³.

i is a switch-knife pivoted to frame *g* at *i*' and having a notch *i*², that is adapted to be engaged by a hook *f*⁴ of lever *f*. The switch-knife *i* is influenced by a spring *i*², which tends to throw the same into engagement with the contacts *j* *k* of a switch which is mounted upon 45 an insulator *l* of frame *g*.

The tracker-bar *c* has a duct *c*' adapted to register with a corresponding perforation of the music-sheet at the end of the piece to be played. The duct *c*' communicates by a tube

p' with bellows *p*², located in a chamber *p*³ of a vacuum-chest *P*. The other chamber, *p*⁴, of the vacuum-chest has a vent *p*⁸ and contains a valve *p*⁵, carrying a pin *p*⁶, adapted to bear upon bellows *p*². The chamber *p*⁴ communicates by a pipe *n*' with suction-bellows *n*, secured to frame *g* opposite lever *f*. To the movable board of bellows *n* is secured a plunger *m*, that passes through a perforation *g*' of frame *g* and is adapted to engage the back of switch-knife *i*.

The operation is as follows: When the lever *f* is tilted by the introduction of a coin in the manner described, it will release knife *i*, and the latter will by its spring *i*² be swung to close the switch. This will start the electromotor, the current traveling as follows: From source of electricity *A* through wire *o*, contact *j*, knife *i*, contact *k*, wire *o*', electromotor *b*, and wire *o*² back to source *A*. When the end perforation of the music-sheet registers with the duct *c*' of the tracker-bar, which is made in addition to the hammer-operating ducts, air is admitted through duct *c*' and the tube *p*' into bellows *p*² to expand the same. This will open valve *p*⁵ by pin *p*⁶ and will 55 close vent *p*⁸. From the vacuum-chamber *p*³ air is constantly withdrawn by a pump, (not shown,) and thus the opening of the valve *p*⁵ will cause a suction in chamber *p*⁴, and consequently through tube *n*' in bellows *n* to collapse the latter and project plunger *m* against switch-knife *i*. The means above described for establishing communication between the exhaust-pipe *n* and the vacuum-chest *P* upon the registration of the perforations in the 60 duct-bridge and the music-sheet are the same as described in Patent No. 741,072, granted to A. P. Roth October 13, 1903. By the motion of the plunger *m* the switch will be 65 opened to arrest the electromotor, and the switch-knife *i* will become reengaged with hook *f*⁴ of lever *f*. The perforation in the music-sheet having passed the perforation *c*' of duct-bridge *c* suction in pipe *n*' ceases and the bellows *n* is expanded by its spring *n*² to 70 withdraw plunger *m*. The parts are thus returned to their normal position (shown in Fig. 1) ready for the introduction of a new coin.

What I claim is—

In a coin-controlled actuating mechanism for autopneumatic pianos, the combination of a tracker-bar having a number of ducts 5 with a vacuum-chest connected to one of said ducts, an exhaust-pipe communicating with the vacuum-chest, bellows communicating with the exhaust-pipe, a plunger connected to the bellows, a switch-knife adapted to be 10 engaged at one side by the plunger, a coin-

controlled lever adapted to engage the other side of the switch-knife, a switch, and a motor in circuit, substantially as specified.

Signed by me at St. Johnsville, Montgomery county, New York, this 7th day of July, 15 1904.

ADAM J. HOBART.
